UNITED STATES PATENT OFFICE.

FREDERICK WILLIAM DUFWA, OF MEXICO, MEXICO.

INTERNAL-COMBUSTION ENGINE.

Application filed May 13, 1926. Serial No. 108,965.

This invention relates to certain new and useful improvements in internal combustion engines and more particularly to the valve structure thereof, the primary object of the invention being to produce a motor wherein the valve structure is of a design to eliminate all hammering noises that are usually present in internal combustion engines of the type employing reciprocating control valves.

With the above and other objects in view that will become apparent as the nature of the invention is better understood, the same consists of the novel form, combination and arrangement of parts hereinafter more fully described shown in the accompanying drawings and claimed.

In the drawings, wherein like reference characters designate corresponding parts throughout the several views,

Figure 1 is a fragmentary front elevational view of an internal combustion engine constructed in accordance with the present invention,

Figure 2 is a side elevational view of the same,

Figure 3 is a vertical cross-sectional view showing the circular valve seat and swinging spherical valve,

Figure 4 is a fragmentary top plan view,

Figure 5 is a detail sectional view showing the valve in the form of a sector of a sphere engaging the ring formation of valve seat,

Figure 6 is a detail sectional view of the valve showing ventilating openings therein,

Figure 7 is cross sectional view of another form of valve carrying shaft wherein heat radiating fins project inwardly of the tubular shaft,

Figure 8 is a fragmentary sectional view showing pipe connections between opposite ends of the tubular valve carrying shaft and the water cooling chambers of the engine cylinder and head,

Figure 9 is a detail sectional view showing the strap connection between the hollow valve and the tubular valve carrying shaft,

Figures 10 and 11 show sectional views of other forms of air cooled valves and shafts, and

Figures 12 and 13 show eccentrically operated valves, respectively, in closed and open positions.

Referring more in detail to the accompanying drawings, there is illustrated an

internal combustion engine, the crank case 1 of which is fragmentarily illustrated, said crank case supporting a cylinder 2 upon the upper end of which the head 3 is mounted, the cylinder and head being provided with the usual water cooling jacket. The crank shaft 4 journaled in the crank case 1 carries the connecting rod 5 that is attached to the piston 6 that works in the cylinder 2 as shown in Fig. 3. The head 3 on the cylinder extends transversely of the upper end of the cylinder and is provided in the opposite ends respectively, with inlet and exhaust openings 7 and 8 while provision is made centrally of the upper side of the cylinder head to accommodate the mounting of the spark plug 9.

The cylinder 2 is provided with the usual bore 10 in which the piston 6 reciprocates, while the head 3 is provided with the usual explosion chamber 11, said head being provided with inlet and exhaust valve controlled openings formed in partition walls spaced from opposite ends of the head forming outer inlet and exhaust chambers 12 and 13 as shown in Fig. 3. The partition wall 14 as shown in detail in Fig. 5 is in the form of an annular flange projecting inwardly from said wall, said flange being threaded 75 80 85 for reception of the externally threaded valve seat ring 15, the operative face of which is of spherical formation as at 15^a.

The valve associated with each ring seat 15 is in the form of a sector of a sphere in which the convex spherical wall 16 is closed 90 by the plane 17, the spherical wall 16 of the valve intimately engaging the spherical face 16 of the valve ring 15, while the latter is adjustable in view of its threaded mounting to compensate for wear and the like. The support for the valve includes a tubular shaft 18 journaled transversely of the cylinder head 3 inwardly of and adjacent to a partition wall 14 and a ring 19 secured to the tubular shaft carries bracket arms 20 attached to the plane wall 17 of the valve, this construction being clearly shown in Figs. 5 and 6.

The operating means for the valve is shown more clearly in Figs. 1 and 2 wherein the cams 21 upon the cam shafts 22 engage roller bearings at the lower ends of the valve lifter rods 23, said rods 23 being polygonal in cross section and working in similarly formed bores in the bearings 24 105 110

and 25 which prevent rotation of said lifting rods. A bracket 26 carries a pair of arms 27 and 28 that are secured to the valve lifting rod 23 at points between the bearings 24 and 25 while a coil spring 29 surrounds the valve lifting rod 23 between the bracket arm 27 and bearing 25 for normally forcing the valve lifting rod 23 in a downward direction into constant engagement 10 with the cam 21 upon the shaft 22. A link 30 is pivotally mounted at its lower end as at 31 upon the upper end of the bracket 26 with the upper end of said link pivoted as at 32 to one end of the lever 33 that is securely attached to the adjacent projecting end of the tubular shaft 18 that supports the valve. The valve operating mechanism for both the inlet and exhaust valves is identical as shown in Figs. 1 and 2. By 20 forming the valve supporting shaft 18 of tubular construction, air is permitted to circulate therethrough for cooling purposes, while, as shown in Fig. 6, the arcuate face 16 of the spherical valve may be provided 25 with ventilating openings 34 for cooling the valve.

The operation of the engine is accomplished in the usual manner, the explosive charge entering the explosion chamber 11 through the inlet port 7, chamber 12 and through the valve controlled opening, the parts being positioned in Fig. 3 at the time of exhausting with the exhaust valve open and the piston 6 at the lower end of the cylinder ready to ascend to discharge or force the spent gas through the exhaust opening 8. The valves being in the form of sectors of spheres with the convex faces thereof working on spherical faces of valve ring 40 seats, all hammering and unnecessary noises are eliminated in the operation of the valves and an effectively silent motor is produced. In addition to the water cooling chamber surrounding the cylinder and head, air circulating through the hollow shaft supporting the valves effectively cools the same while said valve may be further cooled by providing ventilating openings in the convex walls thereof. 45 As shown in Fig. 7, the tubular valve supporting rod 18^a is provided upon the inner face thereof with spaced longitudinally extending radiating fins 18^b which extend into the bore of the tubular shaft to aid in cooling the shaft. 50

Other forms of valves and cooling means therefor are shown in Figs. 8 to 13, and as shown in Figs. 8 to 11, the tubular valve carrying shaft 35 having a lateral opening 60 36 in the side wall thereof intermediate its ends that communicates with the hollow valve 37 that is in the form of a sector of a sphere. The connection between the valve 37 and the tubular shaft 35 is shown in detail in Fig. 9, the rear wall of the valve em-

bodying a body portion 38 that carries curved straps 39 intimately contacting the tubular shaft and having a gas and water pipe connection therewith. The ends of the attaching strap 39 extending beyond the opposite closed side of the tubular shaft 35 are connected by tie bolts 40 to hold the valve rigidly upon the shaft while portions of the contacting faces of the shaft and straps are roughened to prevent rotary movement of the valve relative to the carrying shaft. 70 75

As shown in Figs. 8 and 9, the casting 41 forming the inner wall of the water chamber of the engine head 3 has a portion thereof internally threaded for the reception of the removable valve seat 42 with which the curved wall of the hollow valve 37 cooperates while said valve seat is effectively cooled by contact with the inner wall of the water chamber. Pipe sections extend between the cylinder and head, and the tubular valve carrying shaft as shown in Fig. 8, each end of the shaft 35 carrying a nipple 43 extending outwardly of the shaft ends with a water tight bearing therein, one nipple having a pipe connection 44 with the water cooling chamber of the cylinder 2 while the other nipple 43 has a pipe connection 45 with the water cooling chamber of the head 3. It will therefore be seen that the cooling medium freely flows through the tubular shaft 35 that forms communication between the water chambers of the cylinder and head, the cooling medium passing 100 through the side opening 36 in the shaft 35 to enter the hollow valve 37 as will at once be evident from an inspection of Figs. 8 and 9. 90 95

In the form of the invention shown in Fig. 10, and intended only for the escape valve, air is caused to flow through the tubular valve shaft 35 while a diagonally disposed fin 46 extending from one side of the lateral shaft opening 36 divides the flow of 110 air and causes part of the same to enter the hollow valve 37 to be diffused by the T shaped abutment 47 positioned within the hollow valve. The location of the fin 46 permits part of the air to pass directly 115 through the tubular shaft 35 while a sufficient quantity of air enters the hollow valve 37 to cool the same and escape through the opening in the middle of the spherical side of the valve. 120

The funnel shaped member 48 shown in Fig. 11 is attached to one end of the tubular shaft 35 and an arrangement of this character is specially designed for aeroplanes. The hollow valve 37 carried by the shaft 35 and communicating therewith as illustrated houses a T shaped abutment 47^a having the leg thereof extending substantially completely transversely of the tubular shaft to cause the entire body of air to be diverted 125 130

into the hollow valve and escape at the opposite end of the shaft.

In the form of valve shown in Figs. 12 and 13, the cylinder head wall 2 has a removable valve seat 49 set therein and with which valve seat the valve 50 is associated. The valve 50 is in the form of a sector of a sphere and has a valve operating rod 51 eccentrically attached thereto and extending 10 diagonally through the cylinder head wall 2 in the bearing 52 with the valve operating means associated with the outer projecting end thereof. In the several forms of valves disclosed, the operating means therefor is 15 the same as illustrated in Figs. 1 and 2.

While there are herein shown and described the preferred embodiments of the present invention, it is nevertheless to be understood that minor changes may be made 20 therein without departing from the spirit and scope of the invention as claimed.

What is claimed as new is:—

1. In an internal combustion engine, an oscillating valve in the form of a sector of 25 a sphere that is rounded upon its operative side, a spherical valve seat cooperating with

the convexed side of the valve and a support for the valve at the concave side thereof.

2. In an internal combustion engine, a crank case, a cylinder carried by the crank case, a head at the upper end of the cylinder, said head having inlet and exhaust ports, a tubular shaft journaled in said head adjacent each port and a swingingly mounted valve on one side of each shaft cooperating 30 with an adjacent port.

3. In a valve structure for internal combustion engines, a tubular valve carrying shaft and a hollow valve in the form of a sector of a sphere carried by one side of the 40 tubular shaft and communicating therewith.

4. In a valve structure for internal combustion engines, a tubular valve carrying shaft and a hollow valve carried by the tubular shaft and communicating therewith, 45 the connection between the valve and shaft including a pair of straps carried by the valve and inclosing the shaft and tie rods connecting the straps.

In testimony whereof I affix my signature.

FREDERICK WILLIAM DUFWA.
